SNOWMOBILE HOOD

Ronald Ponech, Valcourt, Quebec, Canada, assignor to
Bombardier Limited, Valcourt, Quebec, Canada

Filed Oct. 24, 1972, Ser. No. 299,650

Term of patent 14 years

Int. Cl. D12—14

U.S. Cl. D12—7

FIG. 1

FIG. 2

FIG. 3

FIG. 4

FIG. 5

FIG. 1 is a front perspective view from above and one side of a snowmobile hood showing my new design;

FIG. 2 is a front elevational view;

FIG. 3 is a side elevational view, the opposite side being substantially a mirror image thereof.

FIG. 4 is a top plan view to a larger scale; and

FIG. 5 is a rear elevational view thereof, to a larger scale.

I claim:

The ornamental design for a snowmobile hood, as shown and described.
